CLAIM

The ornamental design for a star light, as shown and described.

DESCRIPTION

FIG. 1 is a front perspective view of a star light showing my new design;

FIG. 2 is a rear perspective view thereof in use;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of part 9 shown in FIG. 2.

The dash-dash broken lines in the drawings, showing a chain-like connection in FIGS. 2 and 9, illustrate portions of the star light that form no part of the claimed design. The dash-dot broken lines in FIGS. 2 and 9 are for the purpose of illustrating the boundaries of the enlarged view shown in FIG. 9 and form no part of the claimed design.
